GOLF CART HANDLE

Donald R. Parker, Frankfort, George Karl Petritz, Beulah, and Robert A. Westphal, Frankfort, Mich., assignors to Chamberlin Metal Products Co., Frankfort, Mich., a corporation of Illinois

Filed Nov. 13, 1961, Ser. No. 67,476

Term of patent 14 years

(Cl. D10—8)

FIG. 1 is an isometric view of a golf cart handle showing our new design;

FIG. 2 is a side elevational view of the handle;

FIG. 3 is a top plan view of the handle;

FIG. 4 is an elevation of the handle, as seen from the left of FIG. 2;

FIG. 5 is an elevation of the handle, as seen from the right of FIG. 2;

FIG. 6 is an elevation of the handle, as seen in the direction of the arrows 6—6 of FIG. 2.

We claim:

The ornamental design for a golf cart handle, as shown.
